UNITED STATES PATENT OFFICE.

JOHN C. WILSON, OF BOSTON, MASSACHUSETTS, ASSIGNOR TO THE MUNICIPAL SIGNAL COMPANY, OF PORTSMOUTH, NEW HAMPSHIRE.

SIGNAL-TRANSMITTER.

SPECIFICATION forming part of Letters Patent No. 395,102, dated December 25, 1888.

Application filed September 3, 1888. Serial No. 284,402. (No model.)

To all whom it may concern:

Be it known that I, JOHN C. WILSON, of Boston, county of Suffolk, State of Massachusetts, have invented an Improvement in Signal-Transmitters, of which the following description, in connection with the accompanying drawings, is a specification, like letters on the drawings representing like parts.

This invention has for its object to construct an automatic signal-transmitter whereby by any one of a large number of code-signals may be automatically transmitted.

In accordance with this invention a series of signal-wheels or other signaling-surfaces are arranged to co-operate with a series of contact-pens or equivalents, one contact-pen being provided for each signal-wheel or signaling-surface. Each signal-wheel is herein shown as provided with a single projection, and the wheels are arranged upon a single rotatable shaft, so that the projections will extend spirally around the shaft, or so as to form substantially a complete series around the shaft. The contact-pens normally lie out of the path of movement of the signaling or contacting portions of the signal-wheels, but are arranged to be thrown into such path of movement to engage the said signal-wheels by a suitable selecting-cylinder, which is provided upon its surface with studs or projections arranged to move two or more of the pens into engagement with the respective wheels when in different positions. The selecting-cylinder is fixed to a shaft, to which is also fixed a pointer or arm which moves over or co-operates with a dial. A suitable centering device is provided for the selecting-cylinder, and a motor is employed to revolve the signal-wheels.

Figure 1 shows in plan view a multiple signal-transmitter embodying this invention; Fig. 2, a similar view to Fig. 1, the dial and pointer being removed; Fig. 3, a side elevation of the transmitter shown in Fig. 1, the inclosing-case being shown in section; Fig. 4, a detail of the selecting-cylinder, and Fig. 5 a detail showing several of the signal-wheels arranged on a shaft.

The inclosing-case A is of suitable shape to properly inclose the operating parts. The shaft a is journaled in the inclosing-case, oc-

cupying a vertical position, and having fixed thereon several signal or circuit-changing wheels—as 2 3 4 5, &c.—there being thirteen wheels herein shown. A stop or check wheel, 55 a', is fixed to the shaft a, and also fixed to said shaft is a pinion, a², (see dotted lines, Fig. 2,) and a gear, a³. The pinion a² is engaged and driven by a toothed wheel, a⁴, fixed to a shaft, b, which is connected by a pawl and ratchet, b' b², with the mainspring b³, from which it derives its rotation. The hand-crank c or winding-arm is also fixed to the shaft or sleeve carrying the ratchet-wheel b², so that as the said arm is swung from its normal into its extreme abnormal position, as represented by dotted line, Fig. 2, the ratchet-wheel will be rotated and the spring wound, and as the arm returns to its normal position the wheel a⁴ revolves. The gear a³ engages a 60 pinion, a⁵, fixed to a shaft or arbor, a⁶, upon which shaft is also fixed the escape-wheel a⁷, designed to co-operate with any suitable pallet. This train of gearing and spring forms the motor mechanism by which the shaft a is 65 revolved.

Each circuit-changing wheel 2 3 4 5, &c., has a single projection or contact portion, and the several wheels are arranged upon the shaft a so that the projections of the successive 70 wheels occupy different positions, they being herein shown as arranged spirally. The series of contact-pens d are provided, there being one pen for each circuit-changing wheel. The contact-pens, as herein shown, normally 75 lie out of the path of movement of the contact portions of the said wheels, and are adapted to be moved to enter such path of movement by a selecting-cylinder, f, fixed to a shaft, f', journaled in the inclosing-case. 80 The surface of the cylinder f is provided with studs or projections—such, for instance, as best illustrated in Fig. 4—they being arranged in rows extending from end to end of the cylinder, but being placed only at such points as 85 to bear upon certain pens when moved into engagement therewith.

A dial, g, is provided, suitably marked off or graduated, over which moves a pointer, p, which is fixed to the shaft f' and employed 90 as a device to move the selecting-cylinder.

The circuit-changing wheels and contact-

pens form the circuit-changing device, and for the different signals different combinations of pens are moved into position to co-operate with the said wheels. For example, when the pointer *p* is moved to the point on the dial 116, the vertical row of studs or projections *n* (see Fig. 4) will bear upon the pens, and as the shaft *a* is revolved the wheels 2 4 6 7, &c., will co-operate with the pens and thereby effect the changes in the condition of the circuit. By this form of signal-transmitter a very large number of signals may be transmitted with but a small number of circuit-changing device, and a single dial and pointer employed. The signal selecting-cylinder will have any suitable form of centering device.

In United States Patent No. 320,032, dated June 16, 1885, a signal-transmitter is shown presenting a series of signal-wheels mounted upon a shaft, a series of pens, and a selecting-cylinder; and such combination of elements I do not herein broadly claim.

I claim—

1. In a signal-transmitter, a series of circuit-changing wheels, each having a single contact portion and arranged to occupy different relative positions on the shaft, and a series of contact-pens for the circuit-changing wheels, combined with a selecting-cylinder having thereon studs or projections arranged in longitudinal rows, each row having two or more studs or projections to move two or more of the contact-pens into co-operation

with the said circuit-changing wheels at a 35 time, substantially as described.

2. In a signal-transmitter, a series of circuit-changing wheels, each having a single contact portion and each arranged to occupy a different relative position, and motor mechanism for revolving said circuit-changing wheels, and a series of contact-pens for the circuit-changing wheels, combined with a single selecting-cylinder having thereon studs or projections arranged in rows extending from 40 end to end of the cylinder and adapted to move different combinations of pens into position to co-operate with the said circuit-changing wheels, a pointer, and a dial, substantially as described.

3. In a signal-transmitter, a series of circuit-changing wheels and a series of contact-pens for the circuit-changing wheels, combined with a selecting-cylinder having thereon longitudinal rows of studs or projections, 45 each row comprising two or more studs differently placed and arranged to move two or more of the contact-pens into co-operation with the said circuit-changing wheels at a time, substantially as described.

In testimony whereof I have signed my name to this specification in the presence of two subscribing witnesses.

JOHN C. WILSON.
